VENTILATING FIXTURE FOR TELEPHONE BOOTHS

Douglas H. King, Short Hills, N. J., assignor to
Bell Telephone Laboratories, Incorporated, New
York, N. Y., a corporation of New York

Application March 20, 1948, Serial No. 16,126

3 Claims. (Cl. 98—33)

1

This invention relates to a combined ventilating and light fixture unit for use for example in telephone booths and the like.

The object of the present invention is the provision of a combined ventilating and light fixture unit of the type above-referred to which will be simple in construction and efficient in operation.

In the drawing:

Fig. 1 is a view of the combined ventilating and light fixture unit installed into a telephone booth, the booth being shown in perspective;

Fig. 2 is a top view of Fig. 1 shown with the roof removed from the telephone booth and an air exhaust conduit of the ventilating assembly shown with portions broken away;

Fig. 3 is a front view of the ventilating and light fixture unit, the ceiling and roof for the booth and the air exhaust conduit being shown in section taken on line 3—3 of Fig. 2;

Fig. 4 is a partial view of the telephone booth shown in vertical section, different conduits of the ventilating and light fixture unit being shown with portions broken away;

Fig. 5 is a front view of the ventilating assembly shown with the front plate removed and with portions of different air conduits with portions broken away; and

Fig. 6 is a horizontal sectional view taken on line 6—6 of Fig. 4.

In accordance with the construction of the ventilating and lighting fixture unit of this invention, a sheet metal plate is bent laterally at right angles to form the walls 10 and 10y of a casing fitted at a corner of the telephone booth B, as best seen in Figs. 1 and 6, while a diagonally disposed plate 11 forms the front wall of the casing. A bottom wall 12 is secured to the walls 10 and 10y at their lower ends by a molding strip 14 and a plurality of screws 13. The front plate 11 is secured to the parallelly disposed edges of walls 10 and 10y by similar molding strips 14y and screws 15, while the top end portion of plate 11 is secured to a molding strip 16 best seen in Figs. 1, 3 and 4 by a plurality of screws 17, the strip 16 in turn being secured to the ceiling 18 of the booth by a plurality of screws 17'.

The walls 10 and 10y of the casing are formed with lug members 19 and 20 best seen in Figs. 4, 5 and 6 serving for securing an air conduit 21 connecting with an air conduit 22 and an air blower 23. The air conduit 21 extends downwardly and terminates in the form of an elbow curve leading the stream of air generated by the blower 23 toward the person using the telephone booth.

2

A valve 24 in air conduit 21 is adjustable by the rotation of a rod 25 having a knob 26 which may be actuated by the occupant of the booth for controlling the stream of air delivered through a grid 27 at the terminating end of the elbow portion of conduit 21. Conduit 22 as best seen in Figs. 2, 3, 4, 5 and 6 terminates in the form of a nozzle 28, disposed in concentric relation to an enlarged portion of an air conduit 10 29 of rectangular cross-section forming an air exhaust path from two louver plates 32 and 33 at the interior of the booth to a louver plate 30 secured to the exterior of the booth, while another louver plate 31 secured to the top front wall of the booth forms an air conduit extending through the space between the ceiling 18 and roof 18y of the booth to the intake of blower 23.

A plate 34 as best seen in Fig. 4 is secured to the rear side of front plate 11 and to the bottom wall 12 as by screws 35 and 36 to serve for reenforcing the casing thus constructed and as a reflector for a lamp 37 provided for lighting the telephone apparatus as for example a coin collector 38 through a translucent glass plate 40 and the interior of the booth through a translucent glass plate 40y, the energization of the lamp 37 and of the motor for the air blower 23 being effected by the operation of a common switching device not shown controlled by the closing and opening movements of the folding door 41 at the entrance of the booth.

In the operation of the ventilating fixture of this invention, the closure of the telephone booth door is effective to operate a switching device for 35 energizing the motor of the air blower 23 and the lamp 37. The stream of air generated by the operation of the blower is directed into the booth by the air conduit 21 and through the grid 27 toward the subscriber using the booth. The stream of air from blower 23 divides at the junction of air conduits 21 and 22, the latter leading the stream of air towards the nozzle 28 disposed as above-described into the air conduit 29 to exhaust the air from the booth as by a 40 Venturi action in a path including the louvers 32 and 33, the conduit 29 and the louver plate 30 at the top end of the booth, while the air intake path to the blower 23 includes the louver plate 31, the space between the ceiling 18 and the roof 18y of the booth and the open top end portion of the casing. The stream of air from blower 23 to the grid 27 is controlled by the adjustment 45 of air valve 24 which may be moved in position to obtain a maximum amount of air flowing 50 through the grid 27 or moved to the closed posi- 55

tion for completely stopping the flow of air through this grid. However, upon the closure of valve 24, the air stream generated by the blower 23 is now flowing entirely into the air conduit 22 to the nozzle 28 to increase the Venturi effect and thereby accelerating the flow of air from the interior of the booth to the air exhaust louver plate 30 at the top of the telephone booth.

What is claimed is:

1. A ventilating fixture for a telephone booth and the like comprising a casing having an air inlet in one wall thereof, an air blower mounted in said casing, said casing having an opening in the upper portion thereof for supplying air to said blower, a bifurcated air discharge outlet duct, having two branches, connected to said blower, means defining a chamber mounted on the interior of said casing, said chamber having its lower portion communicating with said air inlet, the upper portion of said chamber extending beyond the confines of said casing and serving as an exhaust outlet, one branch of the air discharge outlet duct positioned within said chamber above said air inlet and having a length substantially shorter than the extending portion of said chamber and the other branch of said air discharge outlet duct passing through said casing and communicating with the interior of the booth at a point remote from said exhaust outlet.

2. A ventilating fixture for a telephone booth and the like comprising a casing having a substantially triangular cross section to facilitate corner mounting, said casing having a plurality of air inlets in one wall thereof, an air blower mounted in said casing, said casing having an opening in the upper portion thereof for supplying air to said blower, a bifurcated air discharge outlet duct, having two branches, connected to said blower, means defining a chamber mounted on the interior of said casing, said chamber having its lower portion communicating with said air inlets, the upper portion of said chamber extending beyond the confines of said casing and serving as an exhaust outlet, one branch of the

5 air discharge outlet duct provided with a constricted end portion positioned within said chamber above said air inlets and having a length substantially shorter than the extending portion of said chamber and the other branch of said air discharge outlet duct passing through said casing and communicating with the interior of the booth at a point remote from said exhaust outlet.

10 3. A ventilating fixture for a telephone booth and the like comprising a casing having a substantially triangular cross section to facilitate corner mounting, said casing having a plurality of air inlets in one wall thereof, an air blower mounted in said casing, said casing having an opening in the upper portion thereof for supplying air to said blower, a bifurcated air discharge outlet duct, having two branches, connected to said blower, means defining a chamber mounted 15 on the interior of said casing, said chamber having its lower portion communicating with said air inlets, the upper portion of said chamber extending beyond the confines of said casing and serving as an exhaust outlet, one branch of the air discharge outlet duct positioned within said chamber above said air inlets and having a length substantially shorter than the extending portion of said chamber and the other branch of said air discharge outlet duct passing through 20 the bottom portion of said casing and extending at right angles thereto and communicating with the interior of the booth.
